UNITED STATES PATENT OFFICE

2,368,444

INTERNAL-COMBUSTION ENGINE

Joseph Edward Blanding, New London, Conn., assignor of one-half to Patrick B. McNamara, Groton, Conn.

Application October 19, 1943, Serial No. 506,883

1 Claim. (Cl. 74—57)

This invention relates to internal combustion engines of the four cycle type, the primary object of the invention being to provide a four cycle crankless engine embodying an engine shaft and flywheel, the flywheel being formed with a cam groove in the periphery thereof, and means for transmitting movement of the pistons of the engine, to the flywheel and engine shaft, whereby rectilinear movement of the pistons of the engine, is converted into rotary movement of the engine shaft.

An important object of the invention is to provide a crankless type internal combustion engine, which will increase the power of an engine having cylinders of a given size, over the crank type engine, by increasing the leverage through the driving pin which operates in the cam groove of the flywheel of the engine, and which constitutes an important feature of the present invention.

Another important object of the invention is to provide cross heads in which the driving pin operates, the cross heads being designed to maintain the driving pin in alignment with the cam groove at all times, thereby reducing friction between the driving pin and its cam groove, to a minimum.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawings:

Figure 1 is a partial sectional view through an engine constructed in accordance with the invention, two of the cylinders of the engine being shown in section.

Figure 2 is a sectional view taken on line 2—2 of Figure 1.

Figure 3 is a sectional view taken on line 3—3 of Figure 1.

Figure 4 is a sectional view taken on line 4—4 of Figure 1.

Referring to the drawings in detail, the base of the engine is indicated by the reference character 5, and provides a support for the body portion of the engine, which includes spaced disks 6, secured to the base 5, by means of the plates 7, that are held in place by the bolts 8, spacing bars 8' and circular cover plate 9.

The disks 6 are provided with aligning bearing 55

openings in which the engine shaft 9 is mounted, the engine shaft 9 being also mounted in bearings formed at the upper ends of the standards 10 which are also bolted to the base 5, by means of the bolts 11.

Mounted on the engine shaft, at opposite sides of the body of the engine are hollow shafts 12, that are formed with gears 13 formed with internal teeth that mesh with the gears 14, mounted on stub shafts 15 that extend laterally from the body of the engine. These gears 14, mesh with the gears 16 that are mounted on the engine shaft. Thus it will be seen that as the engine shaft rotates, rotary movement will be imparted to the hollow shaft 12. Cam rings 17 and 18 are mounted on the hollow shaft 12, and are mounted to engage the rocker arms 19 that operate the valve tappets 20, through the rods 21 shown as positioned between the rocker arm 19 and tappets 20. These tappets 20 engage the valve stems 22 and operate the valves 23 at predetermined intervals, the valves 23 being mounted in the cylinder heads 24 that in turn are mounted on the cylinders 25 that extend laterally from the body of the engine, as clearly shown by Figure 1 of the drawings.

The reference character 26 designates the flywheel of the engine, which is mounted on the engine shaft, at points intermediate the ends of the engine shaft, and within the body of the engine. This flywheel is formed with a cam groove 27 that extends around the periphery of the flywheel.

The cylinders 25 are arranged in pairs, the cylinders of each pair being opposed, and arranged in line, so that a piston rod, common to the cylinders of each pair, may be used. The piston rod of one pair of cylinders, is indicated by the reference character 28 and is shown as having connection with the opposed pistons 29. The piston rods of the various pistons operate between the guideways 30 that are arranged between the disks 6 of the body of the engine, directly opposite to the inner ends of the cylinders of the engine. These guideways 30 are formed with grooves, in which the annular rib 31 of the bearing 32 moves. The bearing 32 is mounted on the driving pin 33 that has an extension 34 of a width to fit closely within the cam groove 27, of the flywheel 26. Shoulders are formed on the driving pin, and provide a bearing surface for the balls 35 on which the bearing 32 rests. At the opposite end of the driving pin, is a bearing 36 held in position by the nut 37, the bearing 36 providing a bearing

surface for the balls 38, to insure free rotation of the driving pin on its piston rod.

The cylinders 25 are positioned in circular lines on the outer surfaces of the body of the engine and are spaced equidistant from a central bore of the body, in which the engine shaft 9 operates, and while I have in the present showing, illustrated four cylinders, the number of cylinders may be varied, to meet various engine requirements.

What is claimed is:

In a crankless internal combustion engine, a body, an engine shaft extending through the body, a flywheel having a cam groove formed in the periphery thereof and extending around the said flywheel, secured on the engine shaft and being disposed within the body, a plurality of pairs of opposed engine cylinders mounted on the body, the cylinders of each pair being in direct alignment, pistons operating within the cylinders, a connecting rod common to the pistons, operat-

ing in the respective pairs of cylinders, spaced parallel guide members secured between the inner ends of adjacent opposed cylinders, said guide members having longitudinal grooves formed in 5 the inner surfaces thereof, a driving pin mounted on each rod, and including a bearing member, an annular rib on the bearing member, said annular rib being disposed within the grooves of adjacent parallel guide members, said bearing member having upper and lower ball bearing grooves, a 10 driving pin extending through said bearing member and having ball bearing grooves cooperating with the grooves of the bearing member in housing ball bearings, providing an anti-friction driving pin, and said pin having a reduced end providing a shoulder, said reduced end of the driving pin being adapted to operate in the cam groove of the flywheel, converting reciprocating movement of the pistons to rotary movement of the flywheel and engine shaft.

JOSEPH EDWARD BLANDING.
